ATTORNEY

UNITED STATES PATENT OFFICE.

ARDEN C. PAGE, OF CINCINNATI, OHIO.

COMB.

Application filed October 1, 1924. Serial No. 741,016.

To all whom it may concern:

Be it known that I, ARDEN C. PAGE, a citizen of the United States, residing at Cincinnati, in the county of Hamilton and State of Ohio, have invented new and useful Improvements in Combs, of which the following is a specification.

My invention relates to combs and its principal object is to provide a heated comb which is to be used for the purpose of drying, straightening or dressing the hair.

A further object of the invention is to provide a hair dressing comb of this character wherein the handle is arranged at an angle and thereby facilitating the use of the comb and at the same time allowing the operator's hand to be disposed at a maximum distance from the heated part of the device.

Another object of the invention is to provide a heated comb of this character which is formed with a solid metallic head adapted to be heated and a plurality of tines or comb teeth extending at an angle therefrom.

With the preceding and other objects and advantages in mind the invention consists in the novel combination of elements, construction and arrangement of parts and operation hereinafter more fully referred to and claimed and illustrated in the accompanying drawings wherein:

Figure 1 is an elevation of a comb constructed in accordance with my invention;

Figure 2 is a view partly in longitudinal section and partly in elevation of the device; and

Figure 3 is a transverse sectional view taken on the line 3—3 of Figure 1.

Referring to the drawings in detail wherein corresponding characters of reference denote corresponding parts throughout the several views, the numeral 5 designates a wooden handle provided with a longitudinal bore 6 through which a relatively long rod 7 extends, the latter extending a relatively great distance beyond the inner end of the handle and provided with screw threads 8.

Extending at right angles to the rod 7 is a solid cylindrical comb body 10 having a threaded opening intermediate its ends which is received on the threaded end 8 of the rod 7. A plurality of tines or teeth 12 are cast with the solid body 10 and extend at an angle therefrom as shown in Figure 2. In connection with the body 10 and teeth 12 it is stated that these parts are formed of any desirable metal having a maximum heat retaining capacity.

A tube 13 is cast with the body 10 and extends at right angle thereto and is received on the bolt 7 with its inner end contacting with the adjacent end of the handle 5.

The lower end of the handle 5 is provided with a recess 14 in which the head of a bolt 7 is countersunk and upon engaging this head by means of a screw driver or the like the tube 13 will be drawn tightly against the handle 5.

In the use of my improved device the body 10 and teeth 12 are heated to the required degree and used in the manner of an ordinary comb, however, the arrangement is such as to apply heat to the hair 75 and yet the heated parts are disposed a sufficient distance away from the operator's hand to avoid discomfort.

While I have shown and described the preferred embodiment of my invention it should be understood that changes and arrangement of parts may be made and that I am only limited by the appended claim.

Having thus described the invention, I claim:

A hair dressing and drying comb comprising a solid body formed from heat conducting material, teeth formed on one side thereof and extending at an angle thereto, a tube extending from the body arranged at right angles thereto, a handle and a bolt passing longitudinally through the handle and tube and engaged with the body.

In testimony whereof I affix my signature.

ARDEN C. PAGE.
